UNITED STATES PATENT OFFICE.

WILLIAM H. NICKERSON, OF BROCKTON, MASSACHUSETTS.

BOOT OR SHOE AND SHANK-STIFFENER THEREFOR.

SPECIFICATION forming part of Letters Patent No. 783,756, dated February 28, 1905.

Application filed October 29, 1904. Serial No. 230,511.

To all whom it may concern:

Be it known that I, WILLIAM H. NICKERSON, of Brockton, in the county of Plymouth and State of Massachusetts, have invented certain new and useful Improvements in Boots or Shoes and Shank-Stiffeners Therefor, of which the following is a specification.

This invention relates to boots and shoes, and particularly to means for stiffening the shank portions thereof. The invention has for its object to provide a shank-stiffener of improved construction imparting to the shank portion of the boot or shoe a high degree of strength and resiliency and at the same time involving a material reduction in the cost of production.

The shank-stiffener which I have illustrated herein is adapted to serve as a pocket or holder for a waterproof filling composition inserted between the portions of the channel-lip which extend along the shank, the said stiffener being shown as applied to a welted shoe, although not restricted to the latter.

Of the accompanying drawings, forming a part of this specification, Figure 1 represents a bottom view of a welted boot or shoe as prepared for the application of the outer sole, the latter not being shown. Fig. 2 represents a section on line 22 of Fig. 1. Fig. 3 represents a perspective view of my improved shank-stiffener.

The same reference characters indicate the same parts in all the figures.

In the drawings which illustrate an application to a welted shoe of one embodiment of the invention, *a* represents the inner sole, *b* the upper, and *c* the welt, of a welted boot or shoe, said parts being united by the usual inseam-stitches *d*, extending through the welt and upper and through the between substance of the inner sole intervening between the edge on which the upper bears and the bottom of the channel *e*, which is formed in the outer sole for the reception of said stitches. The formation of the channel creates a channel-lip *e'*, which extends along the margin of the shank and the fore part of the inner sole and is raised and caused to stand out from the face of the central portion of the inner sole by the inseam-stitches. The outer face of

the shank portion of the sole of a completed boot or shoe while narrower than the fore part is given a more abrupt transverse curvature. To give the outer sole the desired curvature at the shank portion, it is customary 55 to apply a combined shank-stiffener and filling-piece, which not only stiffens the shank, but also increases its thickness between the channel-lips *e'* and imparts the desired transverse curvature to the shank portion of the 60 outer sole.

It is common to employ a shank-stiffener and filling-piece made of two parts, one of which is a strip of leather-board or other non-metallic material adapted to give suitable bulk to 65 the stiffener and filling-piece and a strip of metal attached to the first-mentioned strip and imparting the desired stiffness to the shank. Stiffeners of this character are expensive, owing to the cost of material composing the 70 two parts and the labor of assembling and securing said parts together. Moreover, the non-metallic layer or member of the shank-stiffener is porous and adapted to absorb water. Hence if it becomes wet it swells and 75 exerts such pressure on the outer sole as to strain it and partially draw away the stitches that connect it to the welt.

The shank-stiffener which I have described herein is made as a single resilient piece, preferably of sheet metal, and adapted to stiffen and strengthen the shank and to constitute a resilient yet sufficiently strong and durable support for the shank portion of the outer sole and to retain in said portion the desired 80 transversely arched or crowning form. The stiffener is also adapted to serve as a pocket or holder for a waterproof composition applied to the face of the shank portion of the inner sole, said composition being held in 85 place by the shank-stiffener and adapted to exclude water from the inner sole.

In carrying out my invention I provide a shank-stiffener *f*, which is composed of a single piece of resilient sheet material, preferably steel, formed to cover the greater part of the outer face of the shank portion of the inner sole, as indicated in Fig. 1. In a welted shoe the longitudinal edges of the stiffener are preferably shaped to conform closely to 95 100

the contour of the portions of the channel-lip e' , extending along the shank. The stiffener f is arched transversely, so that while its edges bear upon the inner sole it presents a convex outer surface which supports the shank portion of the outer sole and gives the said shank portion the desired curvature.

The inner surface of the stiffener is separated from the face of the shank portion of the inner sole by a cavity adapted to receive a substantial thickness of waterproof filling material g . The said filling material may be composed of a composition of ground cork and rubber cement, or it may be of any other suitable nature. The filling material is preferably applied in a plastic condition, the stiffener f being laid upon the layer of filling material and pressed inwardly, causing the filling material to adhere to the arched inner surface of the stiffener.

The stiffener is secured to the inner sole by means of tacks or other fasteners h , the stiffeners being provided at one end portion with one or more orifices i' , formed to rigidly engage a tack, and at the other end with one or more longitudinally-elongated slots i . These slots provide for a sliding connection between the stiffener and the inner sole and permit the necessary flexure of the stiffener caused by walking without liability of wrenching the forward fasteners h from the inner sole.

The concave inner side of the stiffener, separated between the edges from the shank portion of the inner sole by a space or cavity, not only provides a pocket for filling material, but also leaves the crown of the stiffener-arch free to move toward and from the inner sole, as required by the flexure of the shank. This freedom of movement is not materially affected by the filling when the latter is of the yielding and compressible nature above described.

It will be seen that the stiffener formed as described is adapted to be applied with the minimum expense of time and labor and that it is relatively inexpensive in construction.

The stiffener may be used without the filling material, if desired.

The use of the stiffener is not limited to welted boots and shoes.

In all cases the longitudinal edges of the stiffener are curved to conform approximately to the edges of those portions of the upper that are attached to the inner sole, the stiffener having a varying width and conforming in area to that part of the shank portion of the inner sole which is located between the edges of the upper.

I claim—

1. A shank-stiffener comprising a resilient plate transversely arched to present a convex shank-supporting outer surface, and a concave inner surface adapted to form one side of a cavity between the stiffener and the inner sole, the longitudinal edges of the stiffener being shaped to conform approximately to the edges of the upper at the shank portion of the inner sole.

2. In a boot or shoe, a resilient, transversely-arched shank-stiffener bearing at its edges on the inner sole and presenting a convex outer surface supporting the shank portion of the outer sole, and a concave inner surface forming one side of a cavity between the stiffener and the inner sole, the edges of the stiffener being shaped to conform approximately to the edges of the upper at the shank portion of the inner sole.

In testimony whereof I have affixed my signature in presence of two witnesses.

WILLIAM H. NICKERSON.
